UNITED STATES PATENT OFFICE.

ROBERT A. THOMPSON AND LUTE P. MORRIS, OF DALLAS, TEXAS, ASSIGNEES
TO INTERNATIONAL MANUFACTURING COMPANY OF TEXAS, OF DALLAS,
TEXAS.

CHURNING DEVICE.

1,343,532.

Specification of Letters Patent. Patented June 15, 1920.

Application filed September 25, 1919. Serial No. 326,235.

To all whom it may concern:

Be it known that we, ROBERT A. THOMPSON and LUTE P. MORRIS, citizens of the United States, residing at Dallas, in the county of Dallas and State of Texas, have invented certain new and useful Improvements in Churning Devices, of which the following is a specification.

This invention pertains to new and useful improvements in churning devices.

The object of the invention is to provide a carrier for the churning receptacle and means for reciprocating the same and to embody in the carrier certain novel and advantageous features making for ease of operation, simplicity, convenience in handling, and economical manufacture.

In carrying out the invention a carrier is formed of a cap and a carrier plate, the latter having a flat lip to facilitate the insertion of the churn can and an upstanding flange to hold said can in place; while the cap has a conical shape and a depending annular flange bearing on the cover of the can and receiving the cover which is also conical. Other features consist of ears on the cap and plate for receiving the connecting bolts and eyes upset from the said cap and plate for receiving the reciprocating springs.

The invention will be more readily understood from a reading of the following specification and by reference to the accompanying drawings, in which an example of the invention is shown, and wherein:

Figure 1 is an elevation of a churning device embodying the invention,

Fig. 2 is a partial elevation of the carrier and can on an enlarged scale,

Fig. 3 is a detail of the cap and can cover,

Fig. 4 is an underside view of the cap,

Fig. 5 is a plan view of the plate,

Fig. 6 is a cross-section on the line 6—6 of Fig. 4, and

Fig. 7 is a cross-section on the line 7—7 of Fig. 5.

In the drawings the numeral 10 designates a circular supporting plate having diametrically opposite ears 11. An upstanding marginal flange 12 is provided on one circumferential edge between the ears, while the other or front edge is flattened to form a lip 13. A churning receptacle or can 14 is placed on the plate and the lip facilitates the

insertion of the can, while the flange 12 holds it against displacement.

A conical cap 15 corresponds in shape to the plate 10 and is provided with diametrically opposite ears 16. An annular flange 17 depends from the margin of the cap. Elongated bolts 18 have their heads engaging in the ears 11 and extend up through the ears 16; the upper ends of the bolts receiving wing nuts 19. The cap is made conical in order to receive the conical cover 20 of the can 14 and the flange 17 is less in diameter than the cover so as to rest thereon and permit the cover to project up into the cap. By screwing down the nuts 19 the plate 10 and cap 15 are drawn toward each other and the cover forced down on the can which is thus clamped in the carrier. The conical cap and cover and the depending flange 19 coact to hold the churning receptacle against lateral displacement at the top.

At the center of the cap and also the plate, an eye 21 is upset from the metal and each receives the one end of coiled spring 22. These eyes form a convenient and inexpensive means of fastening the springs to the carrier. One end of the lower spring 22 is attached to a stationary eye 23; while the upper end of the upper spring is connected with a bracket 24 mounted on an upright support.

When it is desired to remove the can 14 it is only necessary to loosen the nuts 19 sufficiently to swing the lower end of the can outward over the lip 13, which latter being flat permits such a removal more readily than if the flange 12 extended entirely around the plate. When the can is to be placed in the carrier the lip acts as a guide and affords an easy insertion. By provision of the lip a minimum extension of the carrier is gained and thus it is not necessary to rotate the wings to a great extent.

In using the churn the can 14 with its contents are placed in the carrier and the nuts 19 screwed down to fasten the can in place. The operator forces the carrier by pressing on the cap 15, thereby extending the upper spring 22 which brings the carrier up when pressure is relieved on the cap. When the carrier moves upward the momentum is sufficient to send it above a central position, thus extending the lower spring which assists in the next downward stroke. It will

be seen that very little effort is required on the part of the operator and the reciprocation of the can will agitate the contents and efficiently churn in a remarkably short 5 period.

What we claim is:

1. In a churning device, the combination with a churn receptacle, of a supporting plate having an upstanding flange and a flat 10 lip for receiving the bottom of the receptacle, a cap having a depending flange bearing on the cover of the churning receptacle, and connections between the cap and plate for clamping the receptacle in the carrier.
- 15 2. In a churning device, the combination with a churning receptacle, of a supporting plate having an upstanding flange and a flat lip for receiving the bottom of the receptacle, a cap having a depending flange bearing 20 on the cover of the churning receptacle, and connections between the cap and plate

for clamping the receptacle in the carrier, the plate and cap each having an eye upset from the center thereof to connect with a reciprocating spring.

25

3. In a churning device, the combination with a churn receptacle, of a carrier including, a circular supporting plate having a flat lip and diametrically opposite ears, a circular cap having a depending annular 30 flange bearing on the cover of the receptacle and also provided with diametrically opposite ears, bolts extending from the ears of the plate to the ears of the cap and wing nuts mounted on the bolts, the cap and plate 35 each having an upset central eye for attaching a coiled spring thereto.

In testimony whereof we affix our signatures.

ROBERT A. THOMPSON.
LUTE P. MORRIS.
